[57] CLAIM

The ornamental design for a computational module, as shown.

DESCRIPTION

FIG. 1 is a perspective view of the computational module showing our new design.

FIG. 2 is a front view of the computational module of FIG. 1.

FIG. 3 is a top view of the computational module of FIGS. 1 and 2.

FIG. 4 is a bottom view of the computational module of FIGS. 2 and 3.

FIG. 5 is a rear view of the computational module of FIGS. 1—4.

FIG. 6 is a side elevational view of the computational module of FIGS. 1—5.
